UNITED STATES PATENT OFFICE

SAMUEL ELLIS, OF BROOKLYN, NEW YORK

SANITARY PROTECTOR FOR STEMS FOR PIPES, ETC.

Application filed December 29, 1927, Serial No. 243,317. Renewed July 11, 1929.

This invention relates to certain new and useful improvements in sanitary protector caps for the stems of tobacco pipes, cigar holders, etc. The main object is to provide a simple and efficient means designed to prevent the accumulation on, or admission into, said stem, of dust or extraneous matter when the pipe is carried in the pocket, or otherwise placed to one side when not in use.

In the accompanying drawing—

Fig. 1 is a side view of my new protector cap;

Fig. 2 is a longitudinal section through the major axis of the cap;

Fig. 3 is a top plan view;

Fig. 4 is a bottom view;

Fig. 5 is a section on the line 5—5 of Fig. 1.

In general my protective device consists of a cap of a size and design adapted to slide over the end of a pipe stem or the like, to act as a protecting shield. The cap is molded of rubber or the like, which is sufficiently elastic to adapt itself to pipe stems of different sizes. At the entrance end I provide a suitable restriction, so that if a pipe stem of small dimensions is inserted in the body of the socket this restricted part will properly grip the side of the stem or body, so as to exclude dirt and dust from that end. On the other hand, when a large stem is inserted, the wall of this restricted entrance will yield sufficiently to admit it.

Referring to the drawings, 1 represents the main body of my protector cap. 2 is the entrance end, the wall of which is sufficiently restricted to fit on the smaller pipe stems or bits. In the preferred construction I form this restriction by means of an inwardly directed flexible or elastic lip or flange 3, extending entirely around the opening 2. Directly under the lip or flange 3 and within the socket I preferably provide a recess 4, back into which the lip 3 will be folded or rolled (see dotted lines in Fig. 2), when a pipe stem of large size is introduced into the cap. Near

the lower end of the cap I preferably provide opposed notches or corrugations 5—5, to receive the flanges usually provided at the end of a pipe stem to thereby more securely hold the cap on said stem. 6 is a mere slit or puncture preferably provided in the end of the cap opposite the entrance end. The walls of this slit are normally in contact, so as to exclude foreign matter. When it is desired to clean the inside of the cap, the entrance end may be pressed against a hot water faucet, so that hot water may be forced through the cap and be discharged through the slit 6. Thus, any nicotine or dirt that may accumulate within the cap may be thoroughly washed out. The inner end of the cap should be of such size that when the pipe stem is seated it will not stretch the cap enough to open the slit 6.

While I have described the preferred embodiment of my invention, it is in my mind that various modifications may be made without departure from the spirit and scope thereof.

What I claim is:

1. As an article of manufacture, a sanitary protector cap for pipe stems and the like, consisting of an elastic resilient body open at one end to receive the stem of the pipe, the mouth of said opening being restricted, said restriction being in the form of an inwardly directed elastic flange defining said opening.

2. As an article of manufacture, a sanitary protector cap for pipe stems and the like consisting of an elastic resilient body open at one end to receive the stem of the pipe, the mouth of said opening being contracted, said contraction being in the form of an inwardly directed elastic flange around said opening, said body having a flange receiving recess cap directly adjacent to said flange.

3. As an article of manufacture, a sanitary protector cap for pipe stems and the like, consisting of an elastic resilient body open at one end to receive the stem of the pipe and

having a self-closing opening at its opposite end, the mouth of said opening being contracted, and means on the side wall of the cap adjacent the inner end of the pipe stem receiving cavity, for abutting the flanged end of a pipe stem.

4. As an article of manufacture, a sanitary protector cap for pipe stems and the like, consisting of an elastic resilient body open
10 at one end to receive the stem of a pipe, the opposite end having a self-closing opening therein, with means on the inner side wall of the cap adjacent said opposite end for receiving the flanged end of a pipe stem.
